UNITED STATES PATENT OFFICE

FRITZ WAGNER, OF BERLIN-LICHTERFELDE, GERMANY, ASSIGNOR TO FRITZ WAGNER
AND CO., OF BERLIN, GERMANY

VALVE

Application filed April 15, 1929, Serial No. 355,338, and in Germany April 16, 1928.

My invention relates to valves of the types described in my Patent No. 1,605,380, and in my co-pending applications Nos. 162,122 and 162,123, and more particularly to the passage between the fluid supply and the equalizing chamber of such valves. The passage, as described in the last-mentioned application, is restricted at the point where the fluid under pressure issues therefrom, and is throttled by a dog on the valve spindle. I have found that such a passage, the cross-sectional area of which is smallest where the throttling action of the dog occurs, is not always quite satisfactory but that when the largest cross-sectional area is at the throttling point and the passage is restricted at a point in front of the throttling point, the main valve does not hammer or chatter on its seat.

The duration of the throttling period is too long with the restriction at the end of the passage and so the main valve may be subjected to accelerations which may cause chattering.

The throttling action begins at a clearance between the dog on the spindle and the corresponding abutment at the main valve which for a passage of circular section is about one-fourth of the passage diameter. Consequently, it is necessary that the dog and the abutment should move through this distance with respect to each other before the throttling action ceases.

The action of the throttling on the main valve is twofold: It reduces the load on the main valve by reducing the pressure in the equalizing chamber, and it produces a reaction in upward direction which further reduces the load.

It is obvious that these forces will impart to the main valve an upward acceleration which is a function of the duration of the throttling period, or, which is the same, of the relative displacement of the dog on the spindle and its abutment on the main valve. Consequently, such relative displacement should be a minimum.

In a restricted passage as described the maximum amount of fluid which flows to the equalizing chamber per unit of time, is limited by the cross-sectional area of the restric-

tion. The flow velocity in the restriction, however, is high which conflicts with the condition of small relative displacement and, in order to eliminate this, I make the area of the passage a maximum at the point where it is throttled, i. e., I provide an extension beyond the restriction and thereby reduce the velocity of the fluid to such a limit that when the fluid impinges on the dog of the valve spindle its velocity is quite a secondary consideration and practically only the static pressure of the fluid reacts between the dog and its abutment on the main valve.

By providing a passage of this type, i. e., a passage which is widest at the throttling point, very small relative displacement is obtained between the dog and its abutment. By suitably determining the ratio of areas, that is, the ratio of the restricted cross-sectional area of the passage and the area at its end, chattering or hammering of the main valve is absolutely eliminated.

In the accompanying drawings, several types of valves and passages are illustrated by way of example.

In the drawings—

Fig. 1 is an axial section of a valve of the general type shown and described in my said co-pending application No. 162,123 in which the dog on the valve spindle cooperates with a hollow check on the main valve.

Fig. 2 is a longitudinal section of the hollow check,

Fig. 3 is a plan view of the check, viewed from below,

Fig. 4 is an end elevation of the check, these three figures being drawn to a larger scale;

Figs. 5 and 6 are axial sections of valves corresponding to my co-pending application No. 162,122, and my Patent No. 1,605,380, respectively.

Throughout the drawings, 1 is the valve casing, 2 is a liner in the casing, 3 is the main valve which makes a sliding fit in the liner, 7 is its seat in the casing, 4 is the auxiliary valve which is seated in the main valve above a port 6, 5 is the equalizing chamber, and 8 are holes in the liner 2.

10 is the valve spindle, 14 is a dog on the valve spindle, means are provided for con-

necting the spindle with the auxiliary valve, and the main valve is provided with a dog or check against which the dog 14 abuts.

Referring now to Fig. 1, the check at the main valve is constituted by tubes 12 to which the fluid is admitted from the pipe 13 through the holes 8. The passage aforesaid is the bore 17 of each tube, having a restriction 18 and an extension 19 which may be rectangular as shown but may also be circular if desired. 20 is a flat face against which the dog 14 may abut.

In the valve described in my said co-pending application No. 162,123, the dog 14 is acting on a restriction in the cavity of the tubes 12, that is, on the narrowest part of the passage 13—12—5, as mentioned in the introduction and with the drawbacks set out. In the present instance, however, the extension 19 reduces the velocity of the fluid. Obviously the extension may be of any suitable size and shape.

Referring now to Fig. 5, the check on the main valve is constituted by the lower face 21 of a bridge at the top of a chamber 9 in the main valve, and 18 are passages connecting the chamber 9 with the equalizing chamber 5. The dog 14 is here replaced by a piston 31 making a sliding fit in the chamber 9 and having passages or bores 32. The spindle 10 penetrates the top and the bottom plate 11 of the chamber 9. The bores 32 constitute the extension of the passage as their total area is larger than that of the passages 17 in the tubes 12. Throttling occurs between the face 21 at the top of the chamber 9 and the upper face of the piston 31.

Referring now to Fig. 6, this shows a solid dog 14 and a cavity 15 in the top of the chamber 9 which the dog is adapted to enter at some clearance, and 16 is an annular passage between the spindle 10 and a hole in the top of the chamber 9. The area of the annular passage which is larger than the total area of the cavities 17 in the tubes 12, is the extension which prevents hammering or chattering as described.

I claim:

1. A valve, comprising a casing, means for supplying fluid under pressure to said casing, an equalizing chamber, a main valve and an auxiliary valve in said casing, a spindle operatively connected with said auxiliary valve, a hollow member in said main valve adapted to connect said fluid-supplying means with said equalizing chamber and having a perforation at its inner end, a dog on said spindle adapted to throttle at a steadily increasing rate the fluid issuing from said perforation, and a restriction in said member the cross-sectional area of which is less than the area of said perforation.
2. A valve, comprising a casing, means for supplying fluid under pressure to said casing, an equalizing chamber, a main valve and an auxiliary valve in said casing, a spindle operatively connected with said auxiliary valve, a hollow member in said main valve adapted to connect said fluid-supplying means with said equalizing chamber and having a perforation at its inner end, means on said spindle adapted to throttle at a steadily increasing rate the fluid issuing from said perforation, and a restriction in said member the cross-sectional area of which is less than the area of said perforation.

auxiliary valve in said casing, a spindle operatively connected with said auxiliary valve, a hollow member in said main valve adapted to connect said fluid-supplying means with said equalizing chamber and having a perforation at its inner end, means on said spindle adapted to throttle at a steadily increasing rate the fluid issuing from said perforation, and a restriction in said member the cross-sectional area of which is less than the area of said perforation.

In testimony whereof I affix my signature.

FRITZ WAGNER.
